(57) **CLAIM**

The ornamental design for an electric pencil sharpener as shown and described.

DESCRIPTION

FIG. 1 is a right-side view of an electric pencil sharpener showing my new design;

FIG. 2 is a left side view thereof;

FIG. 3 is a front view thereof;

FIG. 4 is a rear view thereof;

FIG. 5 is a top view thereof;

FIG. 6 is a bottom view thereof;

FIG. 7 is a perspective view thereof;

FIG. 8 is another perspective view thereof; and,

FIG. 9 is a bottom perspective view thereof.

The broken lines in the drawings illustrate portions of the electric pencil sharpener which form no part of the claimed design.

1 Claim, 8 Drawing Sheets
